Attorney.

UNITED STATES PATENT OFFICE.

HENRY M. NORTON, OF LOUISVILLE, KENTUCKY, ASSIGNOR OF ONE-HALF
TO EDWARD E. MORRIS, OF SAME PLACE.

RAILWAY-SWITCH SIGNAL.

SPECIFICATION forming part of Letters Patent No. 399,342, dated March 12, 1889.

Application filed November 10, 1888. Serial No. 290,460. (No model.)

To all whom it may concern:

Be it known that I, HENRY M. NORTON, a citizen of the United States, residing at Louisville, in the county of Jefferson and State of Kentucky, have invented certain new and useful Improvements in Railway-Signals; and I do hereby declare the following to be a full, clear, and exact description of the invention, such as will enable others skilled in the art to which it appertains to make and use the same.

My invention relates to improvements in railway-signals; and it consists of the novel combination and arrangement of parts, as will be hereinafter fully described and claimed.

The object of my invention is to provide a simple and inexpensive three-throw signal which is so constructed and arranged that by a simple movement of the operating-lever the arm or blade is adjusted to indicate any one of the series of customary signals to the engineer of an approaching train to warn him of danger.

My invention further contemplates the provision of novel means for signaling the engineer during the night-time, as will be hereinafter fully described.

To enable others to understand my invention, I will now proceed to describe the same in connection with the accompanying drawings, in which—

Figure 1 is an elevation, taken from one side, of a railway-signal embodying my invention. Fig. 2 is a like view looking in the direction indicated by the arrow in Fig. 1. Fig. 3 is a horizontal sectional view on the line *y y* of Fig. 1 to show the operating-lever.

Referring to the drawings, in which like letters of reference indicate corresponding parts in all the figures, 1 designates a vertical stand or frame, preferably of the common kind known as "switch-stands," and which is firmly bolted to one of the ties of a railway-track. On the upper end of this vertical stand or frame is a horizontal top, 2, to which is rigidly and firmly secured a vertical tubular post, 3, which is provided at its upper end with a fixed collar, 4, in which is journaled a horizontal transverse shaft, 5, the latter being arranged at one side of the bore or pas-

sage of the tubular post. To each end of this horizontal shaft 5 is fixed a signal arm or blade, 6 and 7, respectively. These signal arms or blades are preferably tapered slightly, and they are painted in different colors, as is usual in this art, one-half of the arm being preferably colored "red" and the other half "green," as indicated by the dotted line *z* in Fig. 1. Each arm or blade is provided at its upper end with two diagonally-extending arms, 8 and 9, which project from opposite sides of the signal-blade, as shown, and each of which is provided at its outer free end with a lens, 10 and 11, respectively, the color of the lenses corresponding to the colors of the signal-blade—thus one lens in green and the other red.

The diagonal arms of the signal-blade terminate at about the same height above the blade proper, and the upper end of the blade is curved or concave, as at 12, which curve joins or merges into the curve of the round lens-holders.

The horizontal shaft 5 passes through the signal arms or blades at points below the concave upper end, 12, and at the middle thereof, as shown in Fig. 1, and these signal arms or blades are arranged at such an elevation with relation to a lamp, 13, that when the blades are in the vertical position indicated in Fig. 1 the lamp will be exposed to view above the concave end 12 of the signal arm or blade. This lamp 13 is fixed to the upper end of the tubular post 3, and it is so arranged that the lenses thereof, which are of a white color, as is usual, will be in line with one or the other of the colored lenses 10 or 11 of both signal arms or blades, according to the position of said arms or blades with relation to the vertical tubular post. A vertical shaft, 14, is passed longitudinally through this vertical tubular post 3, with its lower end journaled in a suitable bearing, 15, fixed to the upright stand 1, and with its upper end passing above the tubular post, as shown. To the upper end of this vertical longitudinal shaft is fixed a horizontal gear-wheel, 16, which meshes with a similar vertical gear-wheel or a segmental rack, 17, that is fixed to the inner face of one of the signal arms or blades, pref-

- erably the blade 7, to operate the shaft 5 and both signal-blades; or, if desired, this gear-wheel or rack 17 may be fixed to the horizontal transverse shaft 5.
- 5 An operating-lever is fixed to the vertical shaft 14 at a point immediately above the top 2 of the vertical stand. This lever is made in two parts or members, the inner one, 18, of which is fixed to the shaft 14 and the outer 10 member, 19, is pivoted to the outer unconfined end of the inner member, 18, and is adapted to be adjusted at right angles thereto to lock the lever and the shaft 14 against movement.
- 15 My invention is especially adapted for use in connection with a three-throw switch of a railway-track, and with this end in view the lower end of the vertical shaft 14 may be provided with a crank, as shown, or otherwise 20 adapted for connection with the switch; but I do not desire to confine myself to this particular use of my invention, as it may be used with equal advantage in other relations or under different conditions.
- 25 The operation of my improved railway-signal is as follows: The signal arms or blades normally remain in the vertical position indicated in Fig. 1 and the operating-lever assumes the positions shown in Figs. 1 and 2.
- 30 To throw the signal arms or blades to an inclined position on one side of the post, (indicated by the dotted lines A in Fig. 1,) the lever 18-19 is moved to the left and in the position indicated by A, which movement of the 35 lever turns the shaft 14 and the gear-wheels to move the signal blades or arms to the positions indicated, whereby the lenses in one of the arms, 8, of the two blades are adjusted or moved in line with the lenses of the lamp 13.
- 40 When it is desired to give a signal of another character, the lever is moved from the left or the middle position to the right of the post 3, as indicated at B, which thereby turns the 45 shaft 14 and the signal arms or blades, the blades assuming a reversely-inclined position on the opposite side of the vertical post, as indicated by dotted lines at B, and having the lenses in the arms 9 thereof adjusted in line with the lenses of the lamp.
- 50 Changes in the form and proportion of parts and details of construction can be made without departing from the spirit or sacrificing the advantages of my invention.
- The top 2 of the switch-stand is provided 55 with a series of notches, 20, (see Fig. 3,) which are located at suitable intervals to receive the outer member, 19, of the operating-lever after the lever has been turned horizontally to properly adjust the signal arms or blades and 60 when said member 19 is turned to a vertical position. It will be understood that the outer member, 19, of the lever is turned to a hori-
- zontal position in line with the inner member, 18, thereof when it is desired to turn the lever to adjust the signal arms or blades in order that said member 19 may clear the top of the stand 1, and that said member 19 is turned to a vertical position after the arms or blades are adjusted, so that it fits in one or the other of the notches 20 in the stand 1 to lock the lever, the vertical shaft, and the signal arms or blades against movement.
- Having thus fully described my invention, what I claim as new, and desire to secure by Letters Patent, is—
1. In a railway-signal, the combination of a vertical post, a signal-blade, 6, having the diagonal arms 8, 9, provided with lenses arranged on opposite sides thereof and pivoted on the post at a point between said diagonal arms, a fixed lantern arranged at one side of the signal-blade and in the vertical plane of the pivot thereof, and mechanism for moving said signal-blade to an inclined position on either side of the post, and thereby adjusting one or the other of the lenses of said blade in line with the lens of the lantern, substantially as described, for the purpose set forth.
2. In a railway-signal, the combination of a vertical tubular post, the two signal arms or blades 6, 7, carried by a common horizontal shaft which passes centrally therethrough, and each signal-blade having two reversely-inclined arms, 8, 9, each provided with a colored lens, a stationary lantern on the post arranged between the two signal-arms in the vertical plane of the pivot thereof, and a vertical shaft geared directly with the signal-blades for positively moving the latter to an inclined position at either side of the post and adjusting one or the other of the two lenses carried by each blade in line with the lenses of the lantern, substantially as and for the purpose set forth.
3. In a railway-signal, the combination of a fixed stand, 1, having the vertical tubular post 3 fixed thereto, a horizontal transverse shaft journaled on the post at the upper end thereof, the signal-blades each having the diverging lens-holding arms 8 and 9, fixed on said shaft at a point between the arms thereof, a lantern fixed between said arms in the vertical plane of the horizontal shaft, a vertical shaft, 14, passing through the tubular post and geared at its upper end directly to one of the signal-blades, and a lever, 18, 19, fixed to the vertical shaft, substantially as described.

In testimony whereof I affix my signature in presence of two witnesses.

HENRY M. NORTON.
